UNITED STATES PATENT OFFICE

99,013

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corporation of New Jersey

Application December 2, 1935, Serial No. 59,854

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in parallel chain-like bands running

in substantially straight direction through the entire fabric and comprising ridge-like elements on the face of the fabric connected with adjacent elements within the same band by elongated link-like elements, and other ridges of less length than said first ridges in regular arrangement between adjacent bands and parallel thereto.

I claim:

The ornamental design for a textile fabric or similar article of manufacture substantially as shown and described.

JOHN F. GAUL, JR.
